DUAL SERVICE ELEVATOR SYSTEMS

William F. Eames, Westfield, N. J., assignor to Westinghouse Electric Corporation, East Pittsburgh, Pa., a corporation of Pennsylvania

Application November 4, 1952, Serial No. 318,651

45 Claims. (Cl. 187—29)

This invention relates to dual service elevator systems and it has particular relation to an elevator system which automatically selects, in accordance with requirements, one of a plurality of types of elevator service.

Various aspects of the invention are applicable either to an elevator system having a single elevator car or to a system having multiple elevator cars arranged in a bank. Furthermore, aspects of the invention are applicable to elevator systems wherein attendants are provided in the elevator cars for the purpose of operating the elevator cars or to automatic systems wherein the elevator cars may operate without car attendants. Since the invention is particularly suitable for automatic elevators, it will be described with particular reference to an automatic elevator system.

Elevator systems may be called on to handle various traffic patterns. Some of these patterns are discussed in my copending patent application Serial No. 166,620, filed June 7, 1950, which has issued as Patent 2,624,425. To illustrate the various traffic patterns which may be encountered, reference may be made to an apartment building having an elevator system intended to serve a plurality of floors. During a major portion of the day, the calls for an elevator system in the up direction and in the down direction may be comparatively balanced. However, immediately before the start of a business day, substantial numbers of apartment house tenants may desire elevator service to the lower terminal floor for the purpose of proceeding to their places of employment. Under these circumstances, the number of prospective passengers desiring down service may exceed substantially those desiring up service.

Immediately after the close of the business day tenants may return to the apartment building and request transportation from the lower terminal floor to the various upper floors of the building. Under these circumstances, the number of calls for up service may exceed substantially the number of calls for down elevator service.

In accordance with the invention, an elevator system is provided which automatically selects the type of service best suited for various traffic patterns. If the changes in the traffic pattern are repetitive at regular intervals, the type of service rendered by the elevator system may be changed at regular intervals in any suitable manner as by means of a time switch. In most cases, however, it will be found that the changes in traffic patterns occur at irregular intervals. For this reason, the changes in the type of service rendered by the elevator system preferably are made in response to the traffic demand.

Various combinations of types of elevator service may be employed. In a preferred embodiment of the invention, the elevator system may be arranged to provide either a bidirectional selective collective elevator service or a unidirectional selective collective elevator service. In the former type of service, each elevator car is controlled during an up trip to stop successively at each floor which it approaches for which a call is registered by a passenger within the elevator car or by a prospec-

2

tive passenger located at the floor being approached. Similarly, during a down trip the elevator car is conditioned to stop successively at each floor approached by the elevator car for which a call is registered by a passenger within the elevator car or by a prospective passenger located at the floor which is being approached by the elevator car. Each of the trips of the elevator car may be a complete trip between the terminal floors. Alternatively, the system may be so designed that during a trip of the elevator car in one direction, such as the up direction, the elevator car stops at the farthest floor for which any call is registered. Thereafter, the elevator car travels in the opposite or down direction toward the lower terminal floor and collects calls during the down trip in the customary manner.

For unidirectional selective collective operation, the elevator system may be so designed that an elevator car does not accept calls from prospective passengers located at the various floors of the building during one direction of travel of the elevator car. Thus, if the elevator car is loaded at the lower terminal floor, it proceeds upwardly but fails to stop in response to any call for up service registered by a prospective passenger at any of the intermediate floors of the building. If desired, the elevator car may stop in response to car calls which are registered by passengers within the elevator car. During the return trip of the elevator car, stops are made in response not only to calls registered by passengers within the elevator cars, but to calls registered by prospective passengers at the floors approached by the elevator car.

As previously pointed out, the transfer of the elevator system from one type of operation to another type of operation may be in response to a timing device such as a time switch. However, in a preferred embodiment of the invention, the transfer is in accordance with a service demand.

Let it be assumed that the elevator system is arranged to provide as a basic service the bidirectional selective collective operation. In response to a service demand indicating the presence of an unusually large number of passengers desiring service in the down direction, the elevator system may be converted to provide a special service such as the unidirectional selective collective operation.

As a further example, let it be assumed that while the system is arranged to provide the basic service, a pronounced demand for service from the lower terminal floor is received. Under such circumstances, the system may be automatically conditioned to provide a special service expediting the transportation of prospective passengers from the lower terminal floor to the other floors of the building. If desired, the system may be conditioned to ignore all calls for service received from prospective passengers at the other floors of the building. The demand for service from the lower terminal floor may be measured in various ways as by the weight of the passengers on the platform of an elevator car located at the lower terminal floor or by the number of passengers loaded within a predetermined time.

At the time the elevator system is transferred from basic to special service, one or more calls for up service may be registered by prospective passengers at the intermediate floors of the building. In one embodiment of the invention, these calls are stored until the elevator system has completed its special service assignment. Following such completion (which may require only a short time), the elevator system is restored to basic service and proceeds to answer the previously stored calls.

Alternatively, calls for up service which are registered by prospective passengers at the floors of the

building at the time of the transfer from basic to special service or calls for up service which thereafter are registered by such passengers are conditioned to stop the elevator car during down travel thereof. Under such circumstances, the passengers desiring up service are carried to the lower terminal floor. On the next up trip of the elevator car, these passengers are delivered to the floors which they desire to reach.

Preferrably, prospective passengers are notified of the transfer of the elevator system from one type of service to another type of service. For example, when the elevator system is transferred from basic to special service, a buzzer may be operated to notify prospective passengers that the system is arranged for special service operation. Preferably, however, a signal is located at each of the floors served by the elevator system to notify prospective passengers of such transfer. For example, each signal may be an illuminated sign. When the sign is not illuminated, the system is arranged for basic service operation. In response to the transfer of the system to special service operation, the signs are illuminated to inform prospective passengers that the system is conditioned for special service operation.

Signals may be located at each of the floors for each of the elevator cars. Each of the signals indicates the direction in which each associated elevator car will leave the associated floor after stopping at such floor. These signals may be in the form of down floor lanterns located at each of the floors from which elevator cars may move in a down direction and up floor lantern from which each of the cars may move in an up direction.

In accordance with one embodiment of the invention, the elevator system when arranged for special service operation responds to calls registered by passengers within the elevator cars in one direction only of the travel of the elevator cars. Thus an elevator car may be located at the lower terminal floor and thereafter will proceed without stopping to the highest floor for which a call is registered and will stop at such floor. During the return of the elevator car, the car stops at all floors for which calls are registered by passengers within the elevator car or for which calls are registered by prospective passengers located at the various floors. For some of the floors, calls will be registered not only by passengers within the elevator car but by prospective passengers located at such floors. Consequently, one stop at each of these floors serves both classes of passengers and materially increases the efficiency of the elevator system.

It is, therefore, an object of the invention to provide an improved elevator system having automatic transfer between a plurality of types of operation.

It is a second object of the invention to provide an elevator system having automatic transfer between a plurality of types of operation, together with signals for notifying prospective passengers of the type of operation for which the elevator system is conditioned.

It is a third object of the invention to provide an elevator system which is automatically transferred in response to a service demand from bidirectional selective collective operation to unidirectional selective collective operation.

It is a fourth object of the invention to provide a unidirectional selective collective elevator system conditioned to respond to calls for service in one direction from prospective passengers located at floors served by the elevator system during travel of the elevator car in the opposite direction.

It is a fifth object of the invention to provide an elevator system which is automatically transferred from one type of operation to another type of operation, together with means for storing calls for service which can not be answered during the latter type of operation until the system is restored to the first-mentioned type of operation.

It is a sixth object of the invention to provide a unidirectional selective collective elevator system where-

in calls for floors desired by passengers within an elevator car are answered only while the elevator car is conditioned for operation in a predetermined direction.

It is a seventh object of the invention to provide a selective collective elevator system wherein common registering means are employed for calls registered by passengers within an elevator car and by prospective passengers located at floors served by the elevator car.

It is an eighth object of the invention to provide an elevator system which can be transferred from bidirectional selective collective operation to unidirectional selective collective operation and which has signals for indicating the direction of travel of an elevator car from each floor at which it stops.

Other objects of the invention will be apparent from the following description taken in conjunction with the accompanying drawings, in which:

Figure 1 is a schematic view with electrical circuits shown in straight line form of a portion of an elevator system embodying the invention;

Figs. 2 and 3 are schematic views with electrical circuits shown in straight line form of additional portions of the elevator system illustrated in Fig. 1.

Figs. 1A, 2A and 3A are key representations of electromagnetic switches and relays employed in the circuits of Figs. 1, 2 and 3. If Figs. 1A, 2A, and 3A are placed in horizontal alignment with Figs. 1, 2 and 3, respectively, it will be found that the associated coils and contacts of the relays and switches of the horizontally aligned drawings are substantially in horizontal alignment.

Fig. 4 is a schematic view with electrical circuits shown in straight line form illustrating a modification of the elevator system of Figs. 1, 2 and 3.

Fig. 4A is a key representation of relays employed in the circuits of Fig. 4. If Figs. 4 and 4A are placed in horizontal alignment, it will be found that corresponding coils and contacts of the two are substantially in horizontal alignment;

Fig. 5 is a schematic view with electrical circuits shown in straight line form illustrating a further modification of the elevator system illustrated in Figs. 1, 2 and 3; and

Fig. 5A is a key representation of relays employed in the circuit of Fig. 5. If Figs. 5 and 5A are placed in horizontal alignment, it will be found that corresponding coils and contacts of the two figures are in horizontal alignment.

Because of the complexity of the system, a number of conventions have been adopted. Although the invention may be incorporated in an elevator system having various numbers of elevator cars designed to service various floors or landings of a building, the invention will be described with reference to an elevator system employing two cars for the purpose of serving a building having six floors or landings. The elevator cars will be designated by the reference characters A and B.

Inasmuch as similar circuits are provided for each of the elevator cars, a corresponding component for the elevator car B will be identified by the reference character employed for the component associated with the corresponding car A, but preceded by the letter B to indicate that the component under consideration is associated with the elevator car B. It will be understood that the elevator car B and all components specific thereto may be omitted if a single-car system is desired.

Relays and switches are employed which may have a number of sets of contacts which are substantially simultaneously operated. Each set of contacts is identified by the reference character employed by the relay having the contacts followed by a numeral indicating the specific set of contacts. Thus the reference characters U1 and U3 represent the first and third sets of contacts of the up switch U for the elevator car A.

An electromagnetic switch or relay may have make or front contacts. Such contacts are closed when the

switch or relay is energized and picked up. The contacts are open when the switch or relay is deenergized and dropped out. In addition, relays and switches may have break or back contacts. Such contacts are closed when a relay or switch is deenergized and dropped out. The contacts are opened when a relay or switch is energized and picked up.

To facilitate the presentation of the invention, the following apparatus is listed:

Apparatus for car A:

V—speed relay
U—up switch
M—running relay
D—down switch
G—holding relay
E—inductor slowdown relay
F—inductor stopping relay
W—up preference relay
X—down preference relay
70T—non-interference relay
J—reversing relay
DR—door relay
T—Car-call stopping relay
1CR to 6CR—car-call registering relays
S—floor call stopping relay
78U—call-above relay
78—No-call relay

Apparatus common to all cars:

1UR to 5UR—up floor-call registering relays
2DR to 6DR—down floor-call registering relays
DC—special-service relay
2BC—basic-service relay

Figure 1

Figure 1 shows motor control circuits for the elevator cars A and B. For the elevator car A, the control circuits illustrated in Fig. 1 include a speed relay V, an up switch U, a car-running relay M, a down switch D, a holding relay G, a slowdown inductor relay E, an inductor stopping relay F, an up preference relay W, a down preference relay X, a non-interference relay 70T and a door relay DR. The control circuits are energized from a direct-current source of electrical energy represented by two buses L1 and L2. (The buses BL1 and BL2 may be energized from the same source and may be tied to the buses L1 and L2 respectively by conductors LT1 and LT2.)

The elevator car A is connected to a counter-weight 10 by means of one or more ropes 11 which pass over a sheave 12. The sheave 12 is secured to a shaft 13 which is rotated by means of suitable motive means. Although any suitable motive means may be employed, it will be assumed that a variable voltage control is employed to control the energization of a direct-current motor 14 which has its armature 14A secured to the shaft 13. The motor 14 has a field winding 14F which is permanently connected across the buses L1 and L2.

By inspection of Fig. 1, it will be noted that the armature 14A and the armature 15A of a direct-current generator 15, together with a series field winding 15S for the generator are connected in a loop series circuit. The generator also has a field winding 15F which is separately excited for the purpose of controlling the direction and magnitude of the energization of the motor armature 14A.

Because of the large number of circuits employed in an elevator system, it is common practice to provide an elevator system with a floor selector 16. Such a floor selector may include an insulating panel 16P, on which a plurality of rows of contact segments are mounted. The floor selector includes a brush carriage 16C (illustrated in Fig. 1 in its lower terminal position) which is moved relative to the contact segments in accordance with motions of the elevator car. Thus the movement of

the brush carriage relative to the contact segments corresponds on a reduced scale to the movement of the elevator car relative to the floors of the building served by such car. The movement of the brush carriage may be effected by a screw 16S which is mounted for rotation on the panel 16P and which is in threaded engagement with the carriage. This screw is coupled through suitable gearing 16G to the shaft 13 for rotation by the shaft.

10 The brush carriage has a separate brush provided for each of the rows of contact segments. Although only two rows of contact segments are illustrated in Fig. 1, it will be understood that as many rows are provided as are required for the elevator system. For example, as the elevator car proceeds from the lower terminal floor upwardly, a brush bb on the brush carriage successively engages the contact segments b2 to b6. The numerals in the reference characters b2 to b6 represent the floors with which the contact segments are associated. For example, as the elevator car approaches the second floor, the brush bb engages the contact segment b2 to prepare circuits which are completed if the elevator car is to stop at the second floor in response to a call registered by a passenger within the elevator car.

25 As a further example, the brush cc on the brush carriage successively engages the contact segments c2 to c6 which are associated respectively with the second to sixth floors. Thus as the elevator car stops at the second floor in response to a car call, the brush cc engages the contact c2 to complete a cancelling or resetting circuit for the purpose of resetting the car call registered for the second floor.

The shaft 13 also carries a brake drum 17. This 30 brake drum cooperates with a spring-applied electromagnetically-released brake of conventional construction. Thus in Fig. 1, a brake shoe 17S is biased against the drum 17 in braking position by means of a spring (not shown). The shoe has secured thereto a magnetic armature 17M which is associated with a releasing coil or 35 brake coil 17B. When the brake coil 17B is energized by closure of either of the sets of make contacts U1 or D1, the brake shoe 17S is retracted against the bias of the spring to release the brake drum 17 and permit rotation of the shaft 13.

40 Returning to the generator field winding 15F, it will be noted that this field winding is connected across the buses L1 and L2 through a reversing circuit. For example, when the make contacts U2 and U3 are closed, the field winding 15F is connected across the buses with proper polarity for up travel of the elevator car. When the make contacts D2 and D3 are closed, the field winding 15F is connected across the buses with proper polarity for down travel of the elevator car. The energization of the field winding 15F may be effected through the resistor R1 when the resistor is not shunted by the make contacts V1 of the speed relay.

45 The elevator car A contains a plurality of push buttons 1c to 6c for the purpose of registering calls by passengers in the elevator car respectively for the first to sixth floors 50 of the building served by the elevator car. In addition, the elevator car has mounted thereon two inductor relays E and F. These inductor relays may be of conventional construction and are employed respectively for controlling the slowdown and stopping of the elevator car. The inductor slowdown relay E is employed for operating 55 break contacts E1 and E2. This relay has a normally incomplete magnetic circuit. Consequently, energization of the coil of the relay alone is insufficient to operate the contacts. If the elevator car during down travel approaches a floor at which it is to stop, the coil of the slowdown relay E is energized and as the car continues its approach, the inductor relay reaches an inductor plate 60 DEP for such floor. The inductor plate completes a magnetic circuit for the relay which results in opening of the break contacts E2. It will be understood that a

similar inductor plate is provided for each of the floors at which the elevator car A is to stop during down travel. The opening of the contacts E2 initiates a slowdown operation of the elevator car.

If the elevator car A is to stop at a floor during up travel, the coil of the relay E is again energized and when the relay reaches the inductor plate UEP associated with the floor, a magnetic circuit is completed for the relay which results in opening of the break contacts E1. The opening of such contacts initiates a slowdown operation of the elevator car. A similar inductor plate is provided for each of the floors at which the elevator car is to stop during up travel thereof. It will be understood that the inductor plates are mounted in the hoistway at positions selected to provide suitable slowdown distances for the elevator car.

The inductor stopping relay F cooperates in a similar manner with inductor plates DFP and UFP. One of the inductor plates DFP is provided for each of the floors at which the elevator car is to stop for down travel thereof. One of the inductor plates UFP is provided for each of the floors at which the elevator car A is to stop during up travel thereof. Operation of the break contacts F1 and F2 of the stopping relay F initiates a stopping operation of the elevator car. It will be understood that the inductor plates DFP and UFP are positioned in the hoistway at suitable points to stop the elevator car accurately at each of the associated floors.

The speed relay V is connected across the buses L1 and L2 through either of two parallel arms. One of these arms includes make contacts U4 of the up switch U, a limit switch 19 and the break contacts E1 of the inductor slowdown relay E. The limit switch 19 is of conventional construction. It is normally closed and is opened as the elevator car nears its upper limit of travel.

The second arm for the speed relay V includes in series the make contacts D4 of the down switch D, a limit switch 20 and the break contacts E2 of the inductor slowdown relay E. The limit switch 20 is a normally closed cam-operated switch which is opened as the elevator car nears its lower limit of travel.

For the running relay M to be energized, the make contacts DR1 of the door relay DR must be closed to indicate that all of the doors associated with the elevator car A are closed. Initial energization of the running relay M also requires closure of the break contacts 70T1 of the non-interference relay 70T to indicate that the elevator car has remained at its last stop for a sufficient period to permit discharge or entry of passengers, and closure of the break contacts 78-1 of a no-call relay to indicate that a call for elevator service has been registered which the elevator car A can answer.

The energization of the running relay M initially is completed through either of two parallel paths. One of these paths include in series make contacts W1 of the up preference relay W, break contacts F1 of the inductor stopping relay F, normally closed contacts of a limit switch 21, and the coil of the up switch U. The limit switch is a cam-operated switch which is opened as the elevator car A nears its upper limit of travel. When the running relay M is energized through the first path, make contacts U5 close to complete a holding circuit around the contacts 70T1 and W1.

The second path for initially completing the energization of the running relay M includes in series the make contacts X1 of the down preference relay X, the break contacts F2 of the inductor stopping relay F, normally closed contacts of a cam-operated limit switch 22 and the coil of the down switch D. The limit switch 22 is opened as the elevator car nears its lower limit of travel.

Energization of the holding relay G and of the inductor relays E and F require closure of the make contacts M1 to indicate that the car is running. In addition, initial energization of these relays requires closure of one of three sets of contacts. Closure of make contacts T1

5 indicates that the elevator car is to stop at the next floor in response to a registered car call. Closure of make contacts J1 indicates that the elevator car during up travel is to stop and reverse at the next floor which is the farthest floor for which a call is registered. Finally, closure of make contacts S1 indicates that the elevator car A is to stop at the next floor reached by the elevator car in response to a floor call which is registered by a prospective passenger for such floor. When the holding relay G is energized, it closes its make contacts G1 to establish a holding circuit around the contacts T1, J1 and S1.

For the up preference relay W to be energized, break contacts D6 and X2 must be closed. In addition, contacts of a normally closed limit switch 24 must be closed. The limit switch 24 is cam operated to open as the elevator car A nears the upper terminal floor. It should be noted that the up preference relay W during an up trip of the elevator car remains energized as long as the limit switch 24 and the break contacts J2 of the reversing relay J are closed. If the contacts J2 open during such trip before the limit switch opens, the up preference relay W remains energized as long as the make contacts M2 remain closed.

For the down preference relay X to be energized, the break contacts U6 and W2 must be closed and a mechanical limit switch 25 must be closed. The limit switch 25 is normally closed and is cam operated to open as the elevator car A nears its lower terminal floor.

The non-interference relay 70T is energized through the make contacts M3 as long as the elevator car is running. When the contacts M3 open during the stopping of an elevator car at a floor, the relay 70T remains picked up for a predetermined time sufficient to permit entry or discharge of passengers relative to the elevator car. The dropout time of the relay may be determined in any suitable way and is represented by a resistor R2 which is connected across the relay coil.

For the reversing relay J to be energized, the break contacts X3 must be closed to indicate that the elevator car is conditioned for up travel. Also break contacts 78-2 of the no-call relay 78 must be closed to indicate that a call is registered which can be answered by the elevator car A. The initial energization of the relay is effected through make contacts 78U1 as the elevator car A approaches the farthest floor in the up direction for which a call is registered. When energized, the relay J closes its holding contacts J3 for the purpose of establishing a holding circuit around the contacts 78U1. Make contacts G2 of the holding relay G may shunt the contacts 78-2.

The door relay DR is a conventional relay which is connected across the buses for energization through door contacts. Each of the hoistway doors for the elevator car A and the car doors have contacts connected in series with the door relay DR to permit energization of the door relay only when all of the doors are closed and in safe condition.

Floor stations are provided at the floors of the building at which prospective passengers may register calls for service. Thus for the second floor a pushbutton 2U may be operated to register an up floor call. A similar pushbutton is provided for each floor from which an up call may be registered. A pushbutton 2D may be operated at the second floor to register a down floor call. A similar pushbutton may be located at each floor from which down service may be desired. These pushbuttons are common to all cars.

Figure 2

The upper part of Fig. 2 illustrates circuits for registering calls for floors desired by passengers within the elevator car. Registration of a call for such a passenger is effected by operation of one of the car call push buttons 1c to 6c. For example, when the push button 2c is operated, the car-call registering relay 2CR is connected

across the buses L1 and L2. This relay closes its make contacts 2CR1 to establish a holding circuit around the push button 2c. It will be understood that each of the push buttons is biased towards contact open position. Each of the push buttons is similarly associated with one of the car-call registering relays 1CR to 6CR, respectively.

The car-call registering circuits have associated therewith four rows of contact segments which are located on the floor selector 16 (Fig. 1). The rows of contact segments b2 to b6 and c2 to c6 previously were mentioned. In addition, a row of contact segments a1 to a5 are successively engaged by a brush aa during travel of the elevator car and cooperate with circuits for initiating stops of the elevator car during up travel. A row of contact segments d1 to d5 coat with a brush dd for the purpose of cancelling registered car calls which are answered during up travel of the elevator car.

It is believed that the car-call stopping circuits can be understood best by a presentation of representative operations. If the elevator car A is to stop at the second floor during up travel thereof, the relay 2CR is energized and the contacts 2CR1 are closed. As the car approaches the second floor, the brush bb engages the contact segment b2 to complete the following circuit:

L1, 2CR1, b2, bb, W3, DC2, T, M4, L2

The energization of the car-call stopping relay T results in stopping of the elevator car A at the second floor.

As the elevator car nears the second floor, the brush dd engages the contact segment d2 to complete the following circuit:

L1, 2CR1, 2CRN, d2, dd, W4, DC4, M5, L2

The coil 2CRN is a cancelling coil which is wound on the same core with the coil 2CR but which is energized in opposition thereto. Consequently, the energization of the cancelling coil 2CRN results in neutralizing of the coil 2CR and resetting of the registering relay. As the elevator car comes to a stop, the brush bb preferably passes slightly beyond the contact segments b2.

Let it be assumed next that the car call for the second floor is registered during down travel of the elevator car. As the elevator car nears the second floor, the brush aa engages the contact segment a2 to complete the following circuit:

L1, 2CR1, a2, aa, X4, T, M4, L2

The energization of the car-call stopping relay T results in stopping of the elevator car A at the second floor.

As the elevator car A continues to approach the second floor, the brush cc engages the contact segment c2 to complete the following circuit:

L1, 2CR1, 2CRN, c2, cc, X5, M5, L2

The energization of the cancelling coil 2CRN cancels the call at the second floor. As the elevator car comes to a stop, the brush aa preferably passes slightly beyond the contact segment a2.

The car-call registering circuits for the second to the fifth floors are all similar and will be understood from the discussion of the circuits associated with the second floor. Because of this similarity, car-call registering circuits are illustrated in Fig. 2 only for the second and fifth floors.

The car-call registering circuits for the sixth or upper terminal floor may be similar to those for the second floor. However, since the elevator car can not stop at the upper terminal floor during down travel thereof, it follows that contact segments in the a and d rows are not required for the upper terminal floor and are not shown for such floor in Fig. 2.

The car-call registering circuits for the first or lower terminal floor may be similar to those discussed for the

second floor. However, the elevator car can not stop at the lower terminal floor during up travel thereof. For this reason, contact segments in the b and c rows, are not required for the lower terminal floor and are not illustrated for such floor in Fig. 2.

The break contacts DC2 and DC4, when opened, prevent response by the elevator car to registered car calls during up travel thereof. These contacts are open during special service operation of the system. The contacts may be shunted respectively by switches 29 and 30.

The central part of Fig. 2 illustrates up floor call registering circuits for the elevator system. The push buttons 1U to 5U are located respectively at the first to fifth floors and may be operated by prospective passengers desirous of transportation to higher floors. These push buttons are associated respectively with up floor-call registering relays 1UR to 5UR and the relays have cancelling coils 1URN to 5URN associated therewith. These registering circuits cooperate with two rows e2 to e5 and f1 to f5 of contact segments located on the floor selector 16 of Fig. 1. The association of the various components may be understood best by consideration of certain operations. If a prospective passenger located at the second floor desires transportation in the up direction, he presses the push button 2U to energize through the normally-open switch of the push button and the break contacts DC7, the up floor call registering relay 2UR for the second floor. This relay closes its make contacts 2UR1 to establish a holding circuit around the contacts DC7 and the push button 2U. By inspection, it will be noted that the contacts 2UR1 now connect the segment e2 for the elevator car A and similar segments such as the segments Be2 for the remainder of the elevator cars to the bus L1.

As the elevator car A while traveling in the up direction nears the second floor, the brush ee of the floor selector engages the contact segment e2 to complete the following circuit:

L1, 2UR1, e2, ee, W5, DC10, S, L2

40 The energized floor stop call relay S initiates a stopping operation of the elevator car A at the second floor.

Upon continued motion of the elevator car A toward the second floor, the brush ff engages the contact segment f2 to complete the following cancelling circuit:

L1, 2UR1, 2URN, f2, ff, W6, G3, L2

The resultant energization of the cancelling coil 2URN resets the registering relay 2UR. It should be noted that had the elevator car B answered the call at the second floor, the brush Bee would have engaged the contact segment Be2 to initiate a stopping operation of the car B. Furthermore, as the elevator car B neared the second floor, the brush Bff would have reached the contact segment Bf2 to reset the registering relay 2UR.

55 As the elevator car A comes to a stop at the second floor, the brush ee preferably passes slightly beyond the contact segment e2. Preferably, the brush ff remains in engagement with the contact segment f2.

The up floor call registering circuits for each of the intermediate floors are similar to those discussed for the second floor. For this reason, such circuits are illustrated in Fig. 2 only for the second and fifth floors. The circuits may be traced readily by reference to the drawings and to the preceding discussion.

60 Inasmuch as the elevator car A during up travel always stops at the upper terminal floor, a single contact segment e6 is connected permanently to the bus L1. Consequently, as the elevator car A approaches the sixth floor the brush ee engages the contact segment e6 to stop the elevator car at the sixth floor.

65 The up floor call registering circuit for the first or lower terminal floor may be similar to those discussed for the second floor. However, inasmuch as the elevator car A always stops at the first floor during down travel thereof, a contact segment in the e row is not required for the first floor and none is illustrated in Fig. 2.

The lower portion of Fig. 2 shows circuits for registering down floor calls. Such calls are registered by operation of push buttons 2D to 6D to close normally-open push button switches which are located respectively at the second to sixth floors for operation by prospective passengers located at these floors. These push buttons are associated with two rows of contact segments located on each of the floor selectors. For example, the elevator car A has associated therewith two rows of contact segments g_1 to g_5 and h_2 to h_6 which cooperate respectively with brushes gg and hh .

Let it be assumed that a prospective passenger at the second floor presses the push button 2D for the purpose of registering a down floor call. Such operation of the push button connects the down floor call registering relay 2DR across the buses L1 and L2. The relay closes its make contacts to establish a holding circuit around the push button 2D. At the same time, the contacts 2DR1 connect the contact segment g_2 and Bg_2 to the bus L1.

As the elevator car A approaches the second floor while traveling in the down direction, the brush gg engages the contact segment g_2 to establish the following circuit:

L1, 2DR1, g_2 , gg , X6, 34, S, L2

In response to the energization of the floor-call stopping relay S, the elevator car is stopped at the second floor. The purpose of the switch 34 will be pointed out below.

As the elevator car A reaches the second floor, the brush hh engages the contact segment h_2 to complete the following circuit:

L1, 2DR1, 2DRN, h_2 , hh , X7, G3, L2

The energization of the cancelling coil 2DRN results in resetting of the down floor-call registering relay 2DR. As the elevator car A stops at the second floor, the brush gg preferably passes slightly beyond the contact segment g_2 . However, the brush hh preferably remains in engagement with the contact segment h_2 as long as the elevator car A remains at the second floor.

Circuits similar to those discussed for the second floor are associated with each of the push buttons 3D to 5D for the intermediate floors of the building and may be traced readily in Fig. 2. Inasmuch as the elevator car can not stop at the upper terminal floor during down travel, a single contact segment g_1 is connected permanently to the bus L1.

The circuit associated with the push button 6D for the upper terminal floor may be similar to those discussed for the second floor. However, since the elevator car can not stop at the upper terminal floor during down travel, a contact segment in the g row is not required for the sixth floor.

The make contacts DC11 of the special service relay DC are closed when the elevator system is conditioned for special service operation. Closure of the contacts DC11 is employed for notifying prospective passengers at the intermediate floors that the system is conditioned for special service operation. In the embodiment of Fig. 2, a plurality of illuminated signs 2DO to 5DO are connected in series with the make contacts DC11 across the buses L1 and L2. One of these signs is located at each of the intermediate floors. When the signs are extinguished, the elevator system is conditioned for basic service operation. When the signs are illuminated, the system is conditioned for special service operation.

Figure 3

The upper part of Fig. 3 illustrates floor signals for the elevator system. These signals are employed for the purpose of informing prospective passengers at the various floors of the direction in which each elevator car which stops at the floor will leave such floor. Although

various types of signals may be employed, it will be assumed that up floor lanterns 1UL to 5UL are employed for informing prospective passengers at the first to fifth floors, respectively, when the elevator car A is conditioned to leave one of the floors at which it is stopped in the up direction. In an analogous manner, down floor lanterns 2DL to 6DL are located respectively at the second to sixth floors for the purpose of informing prospective passengers at these floors when an elevator car stopped at one of these floors will leave the floor in a down direction.

The up floor lanterns 1UL to 5UL are associated respectively with contact segments j_1 to j_5 located in a row on the floor selector. As the elevator car A proceeds from the lower terminal floor to the upper terminal floor, the contact segments j_1 to j_5 are engaged successively by a brush jj . As the elevator car during up travel approaches a floor, such as the second floor, the brush jj engages the contact segment for such floor (in the assumed case contact segment j_2). Since the elevator car is assumed to be traveling up, the make contacts W7 of the up preference relay are closed. If the elevator car stops at the second floor, the break contacts M6 close to complete a circuit for the floor lantern 2UL across the buses L1 and L2. The illuminated floor lantern advises a prospective passenger at the second floor that the elevator car A will proceed upwardly from the second floor. During up travel of the elevator car, the brush jj thus selects the appropriate floor lantern to indicate at each floor at which the elevator car A stops while conditioned for up travel that the elevator car will leave the floor in the up direction.

The down floor lanterns 2DL to 6DL for the second to sixth floors are associated respectively with contact segments k_2 to k_6 which are located in a row on the floor selector. As the elevator car A proceeds in a down direction from the up terminal floor to the lower terminal floor, the brush hh engages successively the contact segments k_6 to k_2 . If the elevator car A is conditioned for down travel, the make contacts X8 of the down preference relay are closed. Consequently, as the down traveling car approaches a floor such as the second floor at which it is to stop, the brush kk engages the contact segment k_2 . As the elevator car stops at the selected floor (in this case the second floor), the break contacts M6 close to complete an energizing circuit for the floor lantern 2DL. This notifies prospective passengers at the second floor that the elevator car will leave the second floor in the down direction.

Inasmuch as the direction preference relays W and X always determine the direction of travel of the elevator car A, it follows that the proper floor lantern always is selected to indicate the direction in which the elevator car A will leave the floor at which it is stopped.

The central part of Fig. 3 illustrates call-above circuits for the elevator cars. Thus the elevator car A has a call-above circuit 36 which includes in series break contacts of all of the call registering relays for floors above the lower terminal floor. The call-above circuit is associated with contact segments m_1 to m_5 which are located in a row on the floor selector. The call-above circuit controls the energization of a call-above relay 78U which is connected through make contacts W8 between a brush mm which cooperates with the contact segments and the bus L2.

By inspection of Fig. 3, it will be noted that the break contacts of the registering relays are connected between the bus L1 and the contact segment m_1 as follows:

L1, 6DR2, 6CR2, 5UR2, 5DR2, 5CR2, 4UR2, 4DR2, 4CR2, 3UR2, 3DR2, 3CR2, 2UR2, 2DR2, 2CR2, m_1

Each of the contact segment m_1 to m_5 is connected to the call-above circuit at a point such that contacts for the registering relays requiring travel of the elevator car above the floor represented by any contact segment are all located above such contact segment. Thus the contact segment

m5 is connected to the call-above circuit between the break contacts 5UR2 and 5DR2. The contact segment *m4* is connected to the call-above circuit between the break contacts 4UR2 and 4DR2. The remaining connections are clear from Fig. 3. The brush *mm* engages and leaves each of the contact segments during up car travel in advance of the associated floor.

By inspection of Fig. 3, it will be observed that as long as a call is registered requiring traveling of the elevator car to a floor above the position of the elevator car A, the call-above relay 78U can not be energized through the call-above circuit.

When the special service relay DC is operated to place the system on special service operation, it may be desirable to modify the call-above circuit. Such modification of the call-above circuit is effected by make contacts DC12, DC14, DC16 and DC18 which shunt the break contacts in Fig. 3 for the call-above circuit 36 which are associated with up floor call registering relays.

A circuit connects the no-call relay 78 between the contact segment *m1* and the bus L2 through the break contacts 1UR2 and 1CR2. If no call which may be served by the elevator car A is registered the relay 78 is energized and picked up. As long as such a call is registered, the relay is deenergized and dropped out.

The special service relay DC is energized from the buses L1 and L2 through a resistor R3 and through a plurality of parallel arms each associated with one of the intermediate floors of the building. Thus one of the arms contains in series make contacts 2DR4 of the down floor call registering relay for the second floor and a resistor 2R. Another arm contains make contacts 3DR4 of the down floor call registering relay for the third floor and a resistor 3R. Further arms contain make contacts 4DR4, 5DR4 and 6DR4 of the down floor call registering relays for the fourth, fifth and sixth floors and resistors 4R, 5R and 6R respectively.

The resistors are proportioned so that current flowing through a predetermined number of the resistors is required to pick up the relay DC. For present purposes, it will be assumed that currents flowing through at least two of the resistors 2R to 6R are required in order to pick up the special service relay DC. When it picks up, the relay DC closes make contacts DC29 to establish with the break contacts 2BC1 a self-holding circuit.

The basic service relay 2BC determines the return of the elevator system to basic service operation. This relay is connected in series with break contacts 2DR5 to 6DR5 of down floor call registering relays for the floors of the building across the buses L1 and L2. Consequently, as long as no down floor call is registered for a floor of the building, the relay 2BC is energized and picked up.

Operation—Figures 1, 2 and 3

In order to facilitate an understanding of the elevator system, some typical operations of the system now will be considered. It will be assumed first that the elevator car A is located at the first floor and that it is conditioned for up travel (up preference relay W is energized). It will be assumed further that an up floor call is registered at the second floor by operation of the push button 2U (Fig. 2). As a result of its energization, the up floor call registering relay 2UR closes its make contacts 2UR1 to establish a self-holding circuit. Inasmuch as the elevator car A is at the first floor, the brush *mm* (Fig. 3) engages contact segment *m1* associated with the call-above circuit 36. The energization of the up floor-call registering relay for the second floor opens break contacts 2UR2 in the call-above circuit to deenergize the call-above relay 78U and the no-call relay 78.

The up floor-call registering relay also opens its break contacts 2UR3 in the call-above circuit for the car B. However, the present discussion will be confined to the operation of the elevator car A.

Referring to Fig. 1, it will be noted that the deenergized call-above relay 78U maintains its contacts 78U1 open to prevent energization therethrough of the reversing relay J. The no-call relay 78 closes its break contacts 78-1 to permit energization therethrough of the car-running relay M and one of the switches U or D. Contacts 78-2 close to permit energization therethrough of the reversing relay.

It will be assumed that the elevator car A has remained at the lower terminal floor for a time sufficient to permit the non-interference relay 70T to time out and close its break contacts 70T1. It will be assumed further that the doors associated with the elevator car A are all closed and that the door relay DR is energized to close its make contacts DR1. The doors may be of any conventional type. For example, they may be manually opened and spring closed or they may be power operated in both directions, if desired.

Since the contacts 70T1 and DR1 are closed, the following circuit is established:

L1, 70T1, 78-1, W1, F1, 21, U, M, DR1, L2

The energized up switch U closes its make contacts U1 to energize the brake coil 17B for the purpose of releasing the elevator brake. Contacts U2 and U3 close to connect the generator field winding 15F for energization with proper polarity for up travel of the elevator car. Contacts U4 close to complete an energizing circuit for the speed relay V and this relay closes to make contacts V1 shunt the resistor R1. The elevator car now accelerates in the up direction.

Closure of the make contacts U5 establishes a holding circuit for the relays U and M around the contacts 70T1 and W1. Opening of the break contacts U6 has no immediate effect on the system operation.

The energization of the running relay M results in closure of the contacts M1 to prepare the relays G, E and F for subsequent operation. Closure of make contacts M2 and M4 and opening of break contacts M5 have no immediate effect on the operation of the system.

Closure of make contacts M3 energizes the non-interference relay 70T which opens its contacts 70T1. Because of the holding circuit established through the contacts U5, opening of the contacts 70T1 has no immediate effect on the operation.

Referring to Fig. 3, it will be noted that while the elevator car was stopped at the first floor, the up floor lantern 1UL was energized through the circuit

L1, 1UL, j1, jj, W7, M6, L2

to indicate that the elevator car would leave the first floor in the up direction. The energization of the running relay results in opening of the break contacts M6 to extinguish the floor lantern as the elevator car A leaves the first floor.

As the elevator car approaches the second floor, the brush *ee* engages the contact segment *e2* to complete the following circuit (Fig. 2)

L1, 2UR1, e2, ee, W5, DC10, S, L2

The energized floor call stopping relay S closes its make contacts S1 (Fig. 1) to complete an energizing circuit for the relays G, E and F. Energization of the holding relay G results in closure of the make contacts G1 to establish a holding circuit around the contacts S1.

In response to continued movement of the elevator car A toward the second floor, the inductor slowdown relay E is horizontally aligned with the slowdown inductor plate UEP for the second floor to complete a magnetic circuit which results in opening of the break contacts E1. Such opening deenergizes the speed relay V which opens its make contacts V1 to insert the resistor R1 in series with the generator field winding

15F. As a result of the decreased energization of the field winding, the elevator car A slows to a landing speed.

Continued movement of the elevator car A towards the second floor brings the inductor stopping relay F into horizontal alignment with inductor stopping plate UFP for the second floor. The resultant completion of the magnetic circuit for the relay results in opening of the break contacts F1 to deenergize the up switch U and the running relay M.

The up switch U now opens its make contacts U1 to deenergize the brake coil 17B. The brake shoe 17S now is biased against the drum 17. In addition, the make contacts U2 and U3 open to deenergize the generator field winding 15F and the elevator car A stops accurately at the second floor. Opening of the make contacts U4 and U5 and closure of the break contact U6 have no immediate effect on the operation of the system.

The running relay M when deenergized opens its make contacts M1 to deenergize the relays E, G and F. As the car stops the inductor relays may pass slightly beyond their cooperating inductor plates. The holding relay G opens its self-holding contacts G1. Opening of the make contacts M2 and M4 and closure of the break contacts M5 have no immediate effect on the operation of the system.

The make contacts M3 in opening deenergize the non-interference relay 70T and this relay starts to time out. Until the relay times out, the contacts 70T1 remain open to prevent further starting of the elevator car.

In approaching the second floor, the elevator car A causes the brush jj to engage the contact segment J2 (Fig. 3) associated with the up floor lantern 2UL. Consequently, as the elevator car stops the break contacts M6 of the running relay close to complete through the contacts W7, the brush jj and the contact segment j2, an energizing circuit for the up floor lantern. This informs a prospective passenger at the second floor that the elevator car will leave the second floor in the up direction.

Referring next to Fig. 2, it will be noted that as the elevator car A stops at the second floor, the brush jj engages the contact segment j2. Since the holding relay G is energized as the elevator car A approaches the second floor, the make contacts G3 are closed to complete the following cancelling circuit:

L1, 2UR1, 2URN, j2, ff, W6, G3, L2

The energization of the cancelling coil 2URN neutralizes the coil of the relay 2UR and resets the relay.

Next it will be assumed that the call for the second floor was registered by a passenger in the elevator car A while the elevator car A is located at the lower terminal floor instead of a prospective passenger located at the second floor. The registration of the car call would be effected by operation of the push button 2c to complete an energizing circuit for the call registering relay 2CR. The relay 2CR closes its make contacts 2CR1 to establish a self-holding circuit. In addition, the break contacts 2CR2 open (Fig. 3) to deenergize the call-above relay 78U and the no-call relay 78.

The elevator car A starts in the manner previously described. As it approaches the second floor, the brush bb engages the contact segment b2 (Fig. 2) to complete the following circuit:

L1, 2CR1, b2, bb, W3, DC2, T, M4, L2

By reference to Fig. 1, it will be observed that the energized car-call stopping relay closes its make contacts T1 to complete with the closed contacts M1 an energizing circuit for the relays G, E and F. These relays cooperate in the manner previously described to stop the elevator car at the second floor. During the stop-

ping operation, the brush dd (Fig. 2) engages the contact segment d2 to complete the following cancelling circuit:

L1, 2CR1, 2CRN, d2, dd, W4, DC4, M5, L2

The energization of the cancelling coil 2CRN resets the relay 2CR.

If the call for the second floor is the only call registered in the system, the engagement of the brush mm (Fig. 3) with the contact segment m2 as the elevator car A approaches the second floor would result in energization of the call-above relay 78U before the call is cancelled. When energized, the relay 78U closes its make contacts 78U1 (Fig. 1) to energize the reversing relay J. This relay closes its make contacts J1. However, since the make contacts S1 or T1 were closed, closure of the contacts J1 is unnecessary in this particular sequence to stop the elevator car at the second floor. Make contacts J3 close to establish a holding circuit around the make contacts 78U1.

Cancellation of the single call for the second floor would result in energization of the no-call relay 78 (Fig. 3) and opening of contacts 78-2 (Fig. 1). However, contacts G2 bypass the contacts 78-2 at this time.

It will be noted that energization of the reversing relay results in opening of the break contacts J2. As the elevator car A stops, the contacts M2 of the running relay M also open to deenergize the up preference relay W. The deenergized relay W opens its make contacts W1, W3, W4, W5, W6, W7 and W8 and closes its break contacts W2. The closure of the break contacts W2 completes an energizing circuit for the down preference relay X and this relay closes its make contacts X1, X4, X5, X6, X7 and X8 and opens its break contacts X2 and X3. Consequently, the elevator car A now is conditioned for down travel. Dropout of the relay G may be delayed slightly to maintain the relay J energized and the contacts j2 open for a time sufficient to assure the above change in direction preference.

By reference to Fig. 3, it will be noted that as the up preference relay is deenergized and the down preference relay is energized, the make contacts W7 open and the make contacts X8 close. Consequently, while the elevator car A is at the second floor, the down lantern 2DL is illuminated to indicate that the elevator car A will leave the second floor in the down direction.

For the next example, it will be assumed that elevator car A is located at the lower terminal floor, an up floor call is registered for the third floor and down floor calls are registered for the fourth and fifth floors. The up floor call for the third floor is registered in the manner discussed for the registration of the up floor call for the second floor. By reference to Fig. 3, it will be noted that the registration of the up floor call for the third floor results in opening of the break contacts 3UR2 in the call-above circuit 36 to deenergize the call-above relay 78U and the no-call relay 78. Similar contacts 3UR3 are open in the call-above circuit B36 for the car B. The relay 78U opens its make contacts 78U1 (Fig. 1) to prevent energization therethrough of the reversing relay J. Contacts 78-1 and 78-2 close.

Referring to Fig. 2, it will be observed that the registration of the down floor call for the fourth floor is effected by pressing the push button 4D which energizes the down floor call registering relay 4DR. This relay closes its self-holding contacts 4DR1. In addition, the break contacts 4DR2 and 4DR3 (Fig. 3) in the call-above circuits 36 and B36 are also opened. It will be noted further that the down floor call registering relay 4DR closes its make contacts 4DR4 and opens its break contacts 4DR5. Closing of the contacts 4DR4 partially energizes the special service relay DC but such energization alone is insufficient to pick up the relay. Deenergization of the basic service relay 2BC results in closure of the break contacts 2BC1 to prepare the holding

circuit for the special service relay DC for subsequent operation.

Referring again to Fig. 2, the down floor call for the fifth floor was registered by operation of the push button 5D to energize the down floor call registering relay 5DR. This relay closes its self-holding contacts 5DR1. In addition, the relay opens its back contacts 5DR2 and 5DR3 (Fig. 3) in the call-above circuits 36 and B36. The relay 5DR additionally closes its make contacts 5DR4 and opens its break contacts 5DR5. The opening of the contacts 5DR5 has no immediate effect on the operation of the system. However, the closure of the make contacts 5DR4 energizes the special service relay DC through the resistor 5R. The special service relay DC now is energized through the two resistors 4R and 5R. Under the assumed conditions such energization is sufficient to pick up the special service relay DC. The relay closes its make contacts DC29, to complete with the contacts 2BC1, a self-holding circuit. The relay DC also closes its make contacts DC12 to DC19 to shunt all contacts of the up floor-call registering relays in the call-above circuits 36 and B36.

As shown in Fig. 2, the energization of the special service relay results in opening of the break contacts DC1, DC2, DC3 and DC4 for the purpose of preventing the elevator cars A and B from answering registered car calls during up travel of the elevator cars. However, for present purposes, it will be assumed that the switches 29, B29, 30 and B30 are closed to shunt these contacts. Consequently, the elevator cars A and B still are conditioned to answer registered car calls during up travel.

The special service relay DC also operates contacts for the purpose of storing registered up floor calls and for the purpose of connecting the up floor call push buttons in parallel with the down floor call push buttons. For example, the break contacts DC5 open to disconnect the up floor-call registering relay 5UR from the push button 5U. If a call is registered by the relay 5UR at the time the contacts DC5 open, such call will continue to be registered or stored.

In addition, the make contacts DC6 close to connect the push button 5U in parallel with the push button 5D. Consequently, operation of either of the push buttons 5U or 5D results in energization of the down floor call registering relay 5DR to register a down floor call.

Contacts of the special service relay similarly are associated with the up floor call push buttons for each of the intermediate floors. As a further example, the break contacts DC7 open to disconnect the push button 2U from the up floor call-registering relay 2UR. Make contacts DC8 close to connect the push button 2U in parallel with the push button 2D for the purpose of energizing by operation of either of the push buttons the down floor call registering relay 2DR.

Since the elevator cars do not stop during up travel at the lower terminal floor, contacts of the special service relay need not be associated with the up floor call push button 1U for the first floor.

The special service relay opens its break contacts DC9 and DC10 to prevent the elevator cars during up travel from answering registered up floor calls. Contacts DC11 close to connect the signs 2DO to 5DO in series across the buses L1 and L2. These signs inform prospective passengers at the various floors that the elevator system is conditioned for special service operation and that the elevator cars answer floor calls only while the elevator cars are conditioned for travel in the down direction.

The elevator car A now starts in the up direction from the lower terminal floor in the manner previously described. As the elevator car A approaches the third floor, the brush ee (Fig. 2) engages the contact segment in the e row for the third floor. However, since the break contacts DC10 are open, the floor-call stopping relay S can

not be energized and the elevator car A passes the third floor without stopping thereat.

The motion of the elevator car A brings the brush mm (Fig. 3) into engagement with the contact segment m4 of the call-above circuit 36. However, since the break contacts 5DR2 are open and are located in the circuit above the contact segment m4, the call-above relay 78U can not be energized at this time.

Next the brush mm engages the contact segment m5 to complete the following circuit:

L1, 6DR2, 6CR2, 5UR2 or DC12, m5, mm, W3, 78U, L2

The energized relay 78U closes its make contacts 78U1 (Fig. 1) to complete an energizing circuit for the reversing relay J. This relay, in turn, closes its make contacts J1 to energize the relays G, E and F. The relays G, E and F cooperate to stop the elevator car A at the fifth floor in a manner which will be clear from the foregoing discussion covering the stopping of the elevator car at the second floor.

The reversing relay J also opens its break contact J2. As the elevator stops, the contacts M2 open to deenergize the up preference relay W. As a result of its deenergization, the relay W closes its break contacts W2 to complete an energizing circuit for the down preference relay X. This conditions the elevator car for down travel. It should be noted that the elevator car is stopping during up travel at a floor in response to a registered down floor call which is the farthest down floor call in the up direction.

As a result of its stop at the fifth floor, the elevator car A operates circuits which result in resetting of the down floor-call registering relay for the fifth floor. This resetting circuit may be traced in Fig. 2, as follows:

L1, 5DR1, 5DRN, h5, hh, X7, G3, L2

The contacts G3 may have a slight delay in dropout to permit closure of the contacts X7 prior to opening of the contacts G3.

As a result of the resetting operation, the down floor-call registering relay 5DR opens its self-holding contacts 5DR1. In addition, the contacts 5DR2 and 5DR3 in the call-above circuits (Fig. 3) reclose. Make contacts 5DR4 open but have no immediate effect on the operation of the system. Contacts 5DR5 reclose but have no immediate effect on system operation.

By reference to Fig. 3, it will be understood that as the elevator car A stops at the fifth floor, the make contacts W7 open and the make contacts X8 close to energize the down floor lantern 5DL. Consequently, this lantern properly indicates the next direction of travel of the elevator car.

After a time sufficient to permit dropout of the non-interference relay 70T (Fig. 1) and after the doors associated with the elevator car A are closed, the following circuit is established:

L1, 70T1, 78-1, X1, F2, 22, D, M, DR1, L2

The energized down switch D closes its make contacts D1 to energize the brake coil for the purpose of releasing the brake. Contacts D2 and D3 close to energize the field winding 15F with proper polarity for down travel of the elevator car. Contacts D4 energize to energize the speed relay V. This relay closes its make contacts V1 to shunt the resistor R1. The elevator car now accelerates in the down direction.

Closure of the make contacts D5 establishes a holding circuit around the contacts 70T1, 78-1 and X1. Opening of the break contacts D6 has no immediate effect on the operation of the system.

The car running relay M operates in the manner previously described.

As the elevator car A proceeds downwardly, the brush

gg engages the contact segment g4 (Fig. 2) to complete the following energizing circuit:

L1, 4DR1, g4, gg, X6, 34, S, L2

The energized floor call stopping relay closes its make contacts S1 (Fig. 1) to complete an energizing circuit for the relays G, E and F. The relay G closes its holding contacts G1 which establish a holding circuit around the contacts S1.

When the inductor slowdown relay E comes into horizontal alignment with the slowdown inductor plate DEP for the fourth floor, a magnetic circuit is completed which results in opening of the break contacts E2 to deenergize the speed relay V. This relay opens its make contacts V1 to introduce the resistor R1 in series with the generator field winding 15F and the elevator car A slows to a landing speed. When the stopping relay F reaches the stopping inductor plate DFP for the fourth floor, a magnetic circuit is completed which results in opening of the break contacts F2 to deenergize the down switch D and the running relay M.

When deenergized, the down switch D opens its make contacts D1 to deenergize the brake coil 17B. Consequently, the brake shoe 17S is applied against the brake drum 17. In addition, the make contacts D2 and D3 open to deenergize the generator field winding 15F and the elevator car stops accurately at the fourth floor. As the car stops the inductor relays may pass slightly beyond the range in which their cooperating magnetic plates complete magnetic circuits therefor.

Opening of the make contacts D4 and D5 and closure of the break contacts D6 have no immediate effect on the operation of the system. The running relay M, when deenergized, operates substantially in the manner previously discussed.

During the stopping of the elevator car A at the fourth floor, the brush hh (Fig. 2) engages the contact segment h4. Inasmuch as the make contacts G2 are closed during the stopping operation, the following cancelling circuit is completed:

L1, 4DR1, 4DRN, h4, hh, X7, G3, L2

As a result of the energization of the cancelling coil 4DRN, the registering relay 4DR is reset and opens its hold contacts 4DR1. Closure of break contacts 4DR2 (Fig. 3) and opening of the make contacts 4DR4 have no immediate effect on the operation of the elevator car A. Closure of the break contacts 4DR3 in the call-above circuit B36 is assumed to have no immediate effect on the operation of the system.

However, resetting of the down floor-call registering relay 4DR results in closure of the break contacts 4DR5 to complete an energizing circuit for the basic service relay 2BC. This relay opens its break contacts 2BC1 to deenergize the special service relay DC.

The special service relay DC opens its make contacts DC20 without immediate effect on the operation of the system. Make contacts DC12 to DC19 open to remove the shunts around the break contacts of the up floor call registering relays in the call-above circuits 36 and B36.

Referring to Fig. 2, it will be noted that the energization of the special service relay DC results in closure of the break contacts DC1, DC2, DC3 and DC4. Under the assumed conditions, such closures have no effect on the operation of the system.

The special service relay, when deenergized, opens make contacts such as the contacts DC6 and DC8 associated with the up floor call push buttons 2U to 5U to disconnect these buttons from the associated down floor-call registering relays. In addition, the break contacts, such as the contacts DC5 and DC7, close to connect the push buttons 2U to 5U to the associated up call registering relays 2UR to 5UR. Thereafter, operation of the up floor call push buttons serves to register calls on the up floor call registering relays.

Closure of the break contacts DC10 permits the elevator car A to answer registered up floor calls during up travel of the elevator car. It will be recalled that following the energization of the special service relay, registered up floor calls were stored by the up floor call registering relays. If such calls are still stored at the time of the deenergization of the special service relay, they may be answered during up travel of one of the elevator cars.

Finally, the opening of the make contacts DC11 deenergizes the signs 2DO to 5DO. Such deenergization of the signs notifies prospective passengers at the intermediate floors that the elevator system is conditioned for basic service operation. It will be understood that the closure of break contacts DC9 permits the elevator car B to answer registered up floor calls during up travel of the elevator car.

It will be assumed that a passenger entering the elevator car at the fourth floor registers a car call for the first floor by operation of the push button 1c. After the lapse of a time sufficient to permit entry and discharge of passengers relative to the elevator car A, the elevator car A proceeds to the lower terminal floor by a sequence of operations which will be clear from the preceding discussion.

A number of alternate operations of the system are possible. For example, let it be assumed that the switches 34 and B34 (Fig. 2) are operated to their dotted line positions. Under such circumstances, the brush gg can be connected to the floor call stopping relay S only if the break contacts DC10 are closed. Consequently, if the special service relay DC is energized to place the system on special service operation, the elevator cars can not stop either during up travel or during down travel in response to registered floor calls. However, should the elevator cars stop in response to registered car calls, any calls registered by the floor call registering relays for the floors at which the elevator cars stop and for the direction of travel of the elevator cars are cancelled. Such operation of the elevator system may be desirable when a large number of prospective passengers at the lower terminal floor desire transportation to higher floors of the building.

Let it be assumed next that the switches 29 and B29, 30 and B30 are opened. As a result of such opening of the switches, the elevator cars are conditioned during up travel to stop in response to registered car calls only if the special service relay DC is deenergized and the system is conditioned for basic operation. This materially increases the efficiency of the system during special service operation.

Each stopping operation of an elevator car consumes substantial time. By reducing the number of stops which the elevator cars are required to make, it is possible to increase materially the efficiency of the system. Consider, for example, the operation of the elevator system when the switches 29, B29, 30 and B30 are opened and when the special service relay DC is picked up. Under such circumstances, the elevator cars do not stop in response to registered up floor calls and they do not stop during up travel in response to registered car calls. Passengers desirous of proceeding to higher floors of the building are carried by an elevator car to the highest registered car call or down floor call. During the return of the elevator car to the lower terminal floor, passengers within the elevator car are distributed to the various floors which they desire and passengers are accepted from the various floors by the elevator cars. Although certain passengers may be required to travel a little longer to reach the floors which they desire, the overall efficiency of the system is materially improved.

The circuits associated with the floor-call registering relays may be identical with those illustrated in Fig. 2, with the exception of the following changes. In Fig. 4, the energization of each of the up floor-call registering relays and the associated cancelling coil for the intermediate floors can be effected only through break contacts of the special service relay DC. For example, energization of the up floor-call registering relay 5UR and of the associated cancelling coil 5URN can be effected only through the break contacts DC5. Consequently, opening of the break contacts DC5 must result in resetting of any call registered by the call registering relay 5UR and must prevent further registration of a call by such relay. It will be assumed that each of the up floor call push buttons for the intermediate floors is connected in parallel to its associated down floor call push button through make contacts of the special service relay which close slightly before the opening of the break contacts of the special service relay associated with the same push buttons. For example, the make contacts DC6 close slightly before the break contacts DC5 open to transfer any call registered by the up floor call registering relay 5UR to the down floor call registering relay 5DR slightly before the contacts DC5 open to reset the relay. Thereafter operation of the push button 5U operates to register a down floor call by energization of the down floor call registering relay 5DR. The break contacts DC7 and the make contacts DC8 are associated in a similar manner with the push button 2U.

The switches 34 and B34 of Fig. 2 are not illustrated in Fig. 4. Finally, break contacts M7 operated by the running relay are employed in place of the make contacts G3 (Fig. 2) associated with the holding relay. The contacts M7 close as the elevator car stops to complete a cancelling circuit for any floor-call registering relay in response to which the elevator car A stops. If desired the make contacts G3 of relay G can be connected in parallel with contacts M7 to prevent registration of a call at the floor where the elevator is stopped from the time of start of slowdown until the car is actually leaving the floor.

Figure 5

As previously explained, the efficiency of the elevator system during unidirectional selective collective operation is materially increased by designing the system to answer calls for service only while elevator cars are conditioned for down travel. This not only results in an improvement in efficiency but it permits a substantial simplification of circuits and a reduction in the number of circuit components required. Such reduction is illustrated in Fig. 5 for the elevator car A. Inasmuch as the elevator car is assumed to provide only unidirectional selective collective operation, contacts of the special service relay DC are not shown.

Car call registering relays 1CR to 6CR and their cancelling coils 1CRN to 6CRN are employed. Since these relays and their associated circuits are similar, only four registering relays 1CR, 2CR, 5CR and 6CR together with their cancelling coils 1CRN, 2CRN, 5CRN and 6CRN are illustrated in the upper part of Fig. 5. These relays and coils are connected in the manner illustrated in Fig. 2 with the following exceptions. Inasmuch as the elevator system does not respond to car calls during up travel thereof, the b and d rows of contact segments are not required and are not illustrated in Fig. 5. This permits elimination of the brushes bb and dd together with the contacts W3 and W4. Contact segment c1 has been added in the c row for engagement by the brush cc as the elevator car reaches the first floor during down travel to energize the cancelling coil 1CRN if a call is registered by the call registering relay 1CR.

In addition, floor call push buttons are connected

in parallel with the car call push buttons for the purpose of energizing the same registering relays. Thus the floor call push buttons 2D to 6D are connected in parallel respectively with the car call push buttons 2c to 6c. Consequently, operation of any of the push buttons 2D to 6D register a call for service by energization of one of the registering relays 2CR to 6CR which is answered while the elevator car A is conditioned for down travel. The floor call push button 1U is connected in parallel with the car call push button 1c. Although this floor call push button 1U is answered during down travel of the elevator car, its operation indicates the desire of a prospective passenger to travel in an up direction. For this reason, it is labeled as an up floor push button. Since the call registering circuits shown in the upper part of Fig. 5 replace all of the call registering circuits associated with the car A in Fig. 2, it is clear that a substantial saving in components and circuits is effected.

The call registering circuits illustrated in Fig. 5 also permit a substantial simplification of the call-above circuit. Thus a call-above circuit 36' is illustrated in Fig. 5 which corresponds to the circuit 36 illustrated in Fig. 3. However, the break contacts of all up floor-call registering relays and the break contacts of all down floor registering relays illustrated for the call-above circuit of Fig. 3 are omitted from the call-above circuit illustrated in Fig. 5. It will be understood that an elevator car controlled by the call-above circuit 36' of Fig. 5 will proceed in the up direction directly to the farthest floor for which a call is registered and will stop at such floor. The elevator car A then reverses and returns to the lower terminal floor answering all registered calls for service during such return.

Although the invention has been described with reference to certain specific embodiments thereof, numerous modifications falling within the scope of the invention are possible.

I claim as my invention:

1. An elevator system comprising a structure having a pair of terminal landings and a plurality of landings intermediate the terminal landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable for moving and stopping only said one elevator car to provide a first predetermined service for all of said intermediate landings, and auxiliary control means responsive to a predetermined service demand for modifying the moving and stopping of the elevator car to provide a second predetermined service for all of said intermediate landings.

2. An elevator system comprising a structure having a pair of terminal landings and a plurality of landings intermediate the terminal landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable for moving and stopping only said one elevator car to provide a substantially balanced service in the two directions of travel of the elevator car for all of said intermediate landings, and second control means responsive to a predetermined service demand for modifying the moving and stopping of the elevator car to provide a service for all of said intermediate landings which is substantially unbalanced in the two directions of travel of the elevator car.

3. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, said elevator car constituting the only elevator car responsive to calls registered by the first and second control means, and modifying means responsive to a predetermined service demand for preventing response by the elevator car to calls registered by the second control means while permitting response by the elevator car to calls registered by the first control means.

4. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from each of the landings for stopping the elevator car as it approaches each of the landings for which the control means is operated while traveling a first direction, second control means operable from each of the landings for stopping only said elevator car as it approaches each of the landings for which the second control means is operated while traveling in a second direction, and modifying means responsive to a predetermined service demand for preventing operation of the second control means from stopping the elevator car while the elevator car is traveling in the second direction, although permitting operation of the first control means to stop the elevator car while the elevator car is traveling in the first direction.

5. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, auxiliary control means for stopping the elevator car during travel in the first direction at landings for which the first control means are operated and for stopping the elevator car during travel in the second direction at landings for which the second control means are operated, and service demand means responsive to a predetermined service demand for modifying said control means to cause the elevator car to stop at landings for which the second control means are operated during travel of the elevator car in the first direction.

6. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predeter-

mined landings, said control means comprising first control means operable from the landings for registering calls for elevator service in a first direction from the landings, second control means operable from the landings for registering calls for elevator service in a second direction from the landings, auxiliary control means for stopping the elevator car during travel in the first direction at landings for which the first control means are operated and for stopping the elevator car during travel in the second direction at landings for which the second control means are operated, and service demand means responsive to a predetermined service demand for modifying said control means to cause the elevator car to stop at landings for which the second control means are operated during travel of the elevator car in the first direction.

7. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, auxiliary control means for stopping the elevator car during travel in the first direction at landings for which the first control means are operated and for stopping the elevator car during travel in the second direction at landings for which the second control means are operated, and service demand means responsive to a predetermined service demand for modifying said control means to prevent the elevator car from stopping during travel in the second direction at landings in response to the operated second control means, said auxiliary control means being effective to maintain registration of operated and unanswered second control means and following termination of the predetermined service condition to stop the elevator car during travel in the second direction at landings for which operation of said second control means is registered.

8. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, first registering means for registering operation of the first control means, second registering means for registering operation of the second control means, and transfer means operable for conditioning the first registering means to register operations of the second control means.

9. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the land-

ings for registering calls for elevator service in a second direction from the landings, first registering means for registering operations of the first control means, second registering means for registering operation of the second control means, and transfer means responsive to a predetermined service demand for conditioning the first registering means to register operations of the second control means.

10. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in the second direction from stopping in response to operated second control means, said elevator car continuing to stop while traveling in the second direction in response to calls registered by the car call means regardless of the condition of the transfer means.

11. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in the second direction from stopping in response to operated second control means, said elevator car continuing to stop while traveling in the second direction in response to calls registered by the car call means regardless of the condition of the transfer means, said auxiliary control means maintaining registration of all operated but unanswered second control means during existence of said predetermined condi-

tion and until the elevator car thereafter answers such operated but unanswered second control means.

12. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in the second direction from stopping in response to operated second control means, said elevator car continuing to stop while traveling in the second direction in response to calls registered by the car call means regardless of the condition of the transfer means, said control means including resetting means responsive to the stopping of an elevator car at a landing for which a call is registered by one of the first and second control means in condition to travel in the direction of such registered call for resetting the one of the first and second control means by which such call is registered, said resetting means being effective for a resetting operation during a stopping operation which is not in response to one of the first and second control means.

13. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in the second direction from stopping in response to operated second control means, said elevator car continuing to stop while traveling in the second direction in response to calls registered by the car call means regardless of the condition of the transfer means,

and means cooperating with the control means in response to arrival of the elevator car during such preventing and during elevator car travel in the second direction at the farthest landing for which a call is registered by one of the first control means and the car call means for stopping the elevator car and reversing the direction of travel of said elevator car at such farthest landing.

14. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in the second direction from stopping in response to operated second control means, said elevator car continuing to stop while traveling in the second direction in response to calls registered by the car call means regardless of the condition of the transfer means, and auxiliary transfer means cooperating with the control means in response to operation of the first-named transfer means for stopping the elevator car during travel in the first direction at landings reached by the elevator car for which calls are registered by the second control means, said control means cooperating with the auxiliary transfer means to reset the associated second control means as the elevator car stops at the last-named landings.

15. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in

the second direction from stopping in response to operated second control means, said elevator car continuing to stop while traveling in the second direction in response to calls registered by the car call means regardless of the condition of the transfer means, said transfer means during such preventing being effective for maintaining the registration of calls registered by the second control means, whereby the elevator car upon termination of the predetermined condition can answer the last-named calls while traveling in the second direction.

16. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in the second direction from stopping in response to operated second control means, said elevator car continuing to stop while traveling in the second direction in response to calls registered by the car call means regardless of the condition of the transfer means, first signal means at each of a plurality of the landings operable when the elevator car stops at one of the landings for indicating that the next movement of the elevator car will be in the first direction, second signal means at each of a plurality of the landings operable when the elevator car stops at one of the landings for indicating that the next movement of the elevator car will be in the second direction, and signal operating means for operating each of the signal means to provide the aforesaid indications.

17. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising car call means operable for registering all calls for landings desired by passengers entering the elevator car, and auxiliary control means cooperating with the car call means to stop the elevator car while the elevator car is conditioned for travel in the first direction at landings reached by the elevator car for which calls were registered by the car call means, said control means being ineffective during travel of the elevator car in the second direction to stop the elevator car in response to a call registered by the car call means for any landing approached by the elevator car which is not the farthest landing for which a call is registered by the car call means.

18. An elevator system comprising a structure having a plurality of landings, an elevator car, means mounting the elevator car for movement in two directions relative

ing approached by the elevator car for which a call is registered by the registering means, car station means actuatable from within the elevator car for operating the registering means to register calls for landings desired by passengers entering the elevator car, landing station means actuatable from the landings for operating the registering means to register calls for elevator service, and auxiliary control means cooperating with the motive means and the registering means during travel only in the first direction of the elevator car to stop the elevator car at each of the landings approached by the elevator car for which a call is registered by said registering means, the same unit of said registering means for each of said landings being operable to register a call for the landing from the landing station means and from the car station means.

24. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first means controlling all of said elevator cars to provide a first similar service for all of the landings, and second means responsive to a predetermined condition for controlling all of said elevator cars to provide a second similar service for all of the landings.

25. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first means controlling all of said elevator cars to provide a first balanced service for all of the landings in the two directions of travel, and second means responsive to a predetermined condition for controlling all of said elevator cars to provide a second unbalanced service for all of the landings in the two directions of travel.

26. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings, second control means common to the elevator cars and operable from the landings for registering calls for elevator service in a second direction from the landings, and means responsive to a predetermined service demand for preventing normal response to calls registered by the second control means by any of the elevator cars normally serving such calls.

27. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings,

second control means common to the elevator cars and operable from the landings for registering calls for elevator service in a second direction from the landings, auxiliary control means for stopping each of the elevator cars during travel in the first direction at each of the landings for which the first control means are operated at the time the elevator car approaches each of such landings and for stopping each of the elevator cars during travel in the second direction at each of the landings for which the second control means are operated at the time the elevator car approaches each of such landings, and service demand means responsive to a predetermined service demand for modifying said control means to cause each of the elevator cars to stop at each of the landings for which the second control means are operated at the time the elevator car approaches each of such landings during travel of the elevator car in the first direction.

28. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings, second control means common to the elevator cars and operable from the landings for registering calls for elevator service in a second direction from the landings, auxiliary control means for stopping each of the elevator cars during travel in the first direction at each of the landings for which the first control means are operated at the time the elevator car approaches each of such landings and for stopping each of the elevator cars during travel in the second direction at each of the landings for which the second control means are operated at the time the elevator car approaches each of such landings, and service demand means responsive to a predetermined service demand for modifying said control means to cause each of the elevator cars to stop at each of the landings for which the second control means are operated at the time the elevator car approaches each of such landings during travel of the elevator car in the first direction, and to prevent each of the elevator cars during travel in the second direction from stopping at landings in response to operation of the second control means, and means cooperating with the second control means in response to arrival of each of the elevator cars while traveling in the second direction at the farthest landing for which the first control means is operated for stopping the elevator car at such farthest landing during the existence of the predetermined service demand.

29. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to all of the elevator cars and operable from the landings by prospective passengers desirous of traveling in a first direction, second control means common to all of the elevator cars and operable from the landings by prospective passengers desirous of traveling in a second direction, first registering means for registering operations of the first control means, second registering means for registering operations of the second control means, 75 and transfer means operable for conditioning the first

registering means to register operations of the second control means.

30. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to all of the elevator cars and operable from the landings by prospective passengers desirous of traveling in a first direction, second control means common to all of the elevator cars and operable from the landings by prospective passengers desirous of traveling in a second direction, first registering means for registering operations of the first control means, second registering means for registering operations of the second control means, auxiliary control means cooperating with the registering means and the motive means to stop the first of the elevator cars to approach a landing in the first direction for which an operation is registered by the first registering means and to stop the first of the elevator cars to approach a landing in the second direction for which an operation is registered by the second registering means, and transfer means responsive to a predetermined service demand for conditioning the first registering means to register operations of the second control means.

31. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings, second control means common to the elevator cars and operable from the landings for registering calls for elevator service in a second direction from the landings, car call means for each of the elevator cars operable for registering calls for landings desired by passengers entering the elevator car, auxiliary control means cooperating with the first control means, the second control means and the car call means for stopping each of the elevator cars during travel in the first direction at landings reached by the elevator car for which calls are registered by the associated car call means or for which the first control means are operated, and for stopping each of the elevator cars during travel in the second direction at landings reached by the elevator car for which calls are registered by the associated car call means or for which the second control means are operated, and transfer means responsive to a predetermined condition for preventing the elevator cars while traveling in the second direction from stopping in response to operated second control means, said elevator cars continuing to stop while traveling in the second direction in response to calls registered by the car call means regardless of the condition of the transfer means.

32. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said

control means comprising first control means common to the elevator cars and operable from the landings for registering calls for elevator service in a first direction from the landings, second control means common to the elevator cars and operable from the landings for registering calls for elevator service in a second direction from the landings, car call means for each of the elevator cars operable for registering calls for landings desired by passengers entering the elevator car, auxiliary control

5 means cooperating with the first control means, the second control means and the car call means for stopping each of the elevator cars during travel in the first direction at landings reached by the elevator car for which calls are registered by the associated car call means or for which the first control means are operated, and for stopping each of the elevator cars during travel in the second direction at landings reached by the elevator car for which calls are registered by the associated car call means or for which the second control means are operated, and transfer means responsive to a predetermined condition for preventing the elevator cars while traveling in the second direction from stopping in response to operated second control means, said elevator cars continuing to stop while traveling in the second direction in response to calls registered by the car call means regardless of the condition of the transfer means, said control means including resetting means responsive to the stopping of each of the elevator cars at a landing for which a call is registered by one of the first and second control means in condition to travel 10 in the direction of such registered call for resetting the one of the first and second control means by which such call is registered, said resetting means being effective for a resetting operation in response to a stopping operation which is not in response to one of the first and second control means.

33. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings, second control means common to the elevator cars and operable from the landings for registering calls for elevator service in a second direction from the landings, car call means for each of the elevator cars operable for registering calls for landings desired by passengers entering the elevator car, auxiliary control means cooperating with the first control means, the second control means and the car call means for stopping each of the elevator cars during travel in the first direction at landings reached by the elevator car for which calls are registered by the associated car call means or for which the first control means are operated, and for stopping each of the elevator cars during travel in the second direction at landings reached by the elevator car for which calls are registered by the associated car call means or for which the second control means are operated, and transfer means responsive to a predetermined condition for preventing the elevator cars while traveling in the second direction from stopping in response to operated second control means, said elevator cars continuing to stop while traveling in the second direction in response to calls registered by the car call means regardless of the condition of the transfer means, and means cooperating with the control means in response to arrival of each of the elevator cars while traveling in the second direction during such preventing at the farthest landing for which any call is registered by the first control means and the

car call means for stopping the elevator car at such farthest landing.

34. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings, second control means common to the elevator cars and operable from the landings for registering calls for elevator service in a second direction from the landings, auxiliary control means responsive to operation of the first control means for successively stopping each of the elevator cars during travel in the first direction at each of the landings for which the first control means are operated at the time the elevator car approaches slowdown distance for each of such landings, said auxiliary control means being responsive to operation of the second control means for successively stopping each of the elevator cars during travel in the second direction at each of the landings for which the second control means are operated at the time the elevator car approaches slowdown distance for each of such landings, transfer means operable in response to a predetermined service demand for preventing the elevator cars during travel in the second direction from stopping in response to operated second control means, and auxiliary transfer means cooperating with the control means in response to operation of the first-named transfer means for stopping each of the elevator cars during travel in the first direction at each of the landings for which the second control means are operated at the time the elevator car approaches slowdown distance for each of the landings in response to such operated second control means, said control means cooperating with the auxiliary transfer means to reset the associated second control means as the elevator cars make the last-named stops.

35. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings, second control means common to the elevator cars and operable from the landings for registering calls for elevator service in a second direction from the landings, auxiliary control means responsive to operation of the first control means for successively stopping each of the elevator cars during travel in the first direction at each of the landings for which the first control means are operated at the time the elevator car approaches slowdown distance for each of such landings, said auxiliary control means being responsive to operation of the second control means for successively stopping each of the elevator cars during travel in the second direction at each of the landings for which the second control means are operated at the time the elevator car approaches slowdown distance for each of such landings, transfer means operable in response to a predetermined service demand for preventing the elevator cars during travel in the second direction from stopping in response to operated second control means, and auxiliary transfer means cooperating

with the control means in response to operation of the first-named transfer means for stopping each of the elevator cars during travel in the first direction at each of the landings for which the second control means are operated at the time the elevator car approaches slowdown distance for each of the landings in response to such operated second control means, first signal means at each of a plurality of the landings for each of the elevator cars, the first signal means for each of the elevator cars being effective when the elevator car is conditioned to move in the first direction from a landing at which it stops to indicate such movement, and second signal means at each of a plurality of the landings for each of the elevator cars, the second signal means for each of the elevator cars being effective when the elevator car is conditioned to move in the second direction from a landing at which it stops to indicate such movement.

36. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable for moving and stopping only said one elevator car to provide a first predetermined service for all of said landings, and auxiliary control means responsive to a predetermined service demand for modifying the moving and stopping of the elevator car to provide a second predetermined service for all of said landings, and signal means comprising a signal device at each of said landings responsive to said auxiliary control means for indicating which of said services the elevator system is conditioned to provide.

37. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from each of the landings for stopping the elevator car as it approaches each of the landings for which the control means is operated while traveling in a first direction, second control means operable from each of the landings for stopping only said elevator car as it approaches each of the landings for which the second control means is operated while traveling in a second direction, modifying means responsive to a predetermined service demand for preventing operation of the second control means from stopping the elevator car while the elevator car is traveling in the second direction, and signal means responsive to said modifying means for indicating at all of said landings the presence of said predetermined service demand.

38. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means operable from the landings for registering calls for elevator service in a first direction from the landings, second control means operable from the landings for registering calls for elevator service in a second direction from the landings, car call means operable for registering calls for landings desired by passengers entering the elevator car, auxiliary control means cooperating

with the first control means, the second control means and the car call means for stopping the elevator car during travel in the first direction at landings reached by the elevator car for which calls are registered by the car call means or for which the first control means are operated and for stopping the elevator car during travel in the second direction at landings reached by the elevator car for which calls are registered by the car call means or for which the second control means are operated, and transfer means responsive to a predetermined condition for preventing the elevator car while traveling in the second direction from stopping in response to operated second control means, said elevator car continuing to stop while traveling in the second direction in response to calls registered by the car call means regardless of the condition of the transfer means, said transfer means comprising signal means for indicating at each of said landings the presence of said predetermined condition.

39. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first means controlling all of said elevator cars to provide a first similar service for all of the landings, and second means responsive to a predetermined condition for controlling all of said elevator cars to provide a second similar service for all of the landings, and signalling means for indicating at all of said landings which of said services the elevator system is conditioned to provide.

40. An elevator system comprising a structure having a plurality of landings, a plurality of elevator cars, means mounting the elevator cars for movement in two directions relative to the structure to serve the landings, and motive means for moving each of the elevator cars relative to the structure, in combination with control means operable in cooperation with the motive means to move the elevator car relative to the structure and to stop the elevator cars for serving predetermined landings, said control means comprising first control means common to the elevator cars and operable from the landings for registering calls for elevator service in a first direction from the landings, second control means common to the elevator cars and operable from the landings for registering calls for elevator service in a second direction from the landings, auxiliary control means for stopping each of the elevator cars during travel in the first direction at each of the landings for which the first control means are operated at the time the elevator car approaches slowdown distance for each of such landings and for stopping each of the elevator cars during travel in the second direction at each of the landings for which the second control means are operated at the time the elevator car approaches slowdown distance for each of such landings, and service demand means responsive to a predetermined service demand for modifying said control means to prevent any of the elevator cars while traveling in the second direction from stopping at said landings in response to said second control means, said service demand means comprising signal means for indicating at said landings the presence of said predetermined service demand.

41. An elevator system comprising a structure having terminal landings and a plurality of intermediate landings located between said terminal landings, an elevator car, mechanism mounting the elevator car for movement in first and second directions relative to the structure to serve the landings, and motive means for moving the elevator car relative to the structure, in combination with control means operable in cooperation with the motive means to move the elevator car relative to the structure

and to stop the elevator car at predetermined landings, said control means comprising first control means at each of the intermediate landings and operable from the intermediate landings for registering calls for elevator service in a first direction from the respective intermediate landings, second control means at each of the intermediate landings and operable from the intermediate landings for registering calls for elevator service in a second direction from the respective intermediate landings, auxiliary control means for stopping the elevator car during travel in the first direction toward a first one of the terminal landings at each landing between the elevator car and such first one of the terminal landings for which the first control means are operated, said auxiliary control means stopping the elevator car during travel in the second direction towards the second one of the terminal landings at each landing between the elevator car and the second one of the terminal landings for which the second control means are operated, said auxiliary control means stopping the elevator car at each of the terminal landings reached by the elevator car and reversing the direction of travel for which the elevator car is set, timing means responsive to expiration of a substantial time of stopping of the elevator car at any of the intermediate landings while a call is registered by the control means for initiating a starting operation of the elevator car, and transfer means operable for preventing the stopping of the elevator car during travel in the second direction at any of the intermediate landings approached by the elevator car in response to any calls registered by the second control means for an intermediate landing, said transfer means when operated permitting the stopping of the elevator car when traveling in the first direction at any of the intermediate landings approached by the elevator car for which a call is registered by the first control means.

42. An elevator system comprising a structure having terminal landings and a plurality of intermediate landings located between said terminal landings, an elevator car, mechanism mounting the elevator car for movement in first and second directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means at each of the intermediate landings and operable from the intermediate landings for registering calls for elevator service in a first direction from the respective intermediate landings, second control means at each of the intermediate landings and operable from the intermediate landings for registering calls for elevator service in a second direction from the respective intermediate landings, auxiliary control means for stopping the elevator car during travel in the first direction toward a first one of the terminal landings at each landing between the elevator car and such first one of the terminal landings for which the first control means are operated, said auxiliary control means stopping the elevator car during travel in the second direction towards the second one of the terminal landings at each landing between the elevator car and the second one of the terminal landings for which the second control means are operated, said auxiliary control means stopping the elevator car at each of the terminal landings reached by the elevator car and reversing the direction of travel for which the elevator car is set, timing means responsive to expiration of a substantial time of stopping of the elevator car at any of the intermediate landings while a call is registered by the control means for initiating a starting operation of the elevator car, and transfer means operating in response to a predetermined service demand for preventing the stopping of the elevator car during travel in the second direction at any of the intermediate landings approached by the elevator car in response to any calls registered by the second control means for an

intermediate landing, said auxiliary control means being effective if the elevator car while traveling in the second direction approaches a landing for which a call is registered by the first control means which is the farthest landing in the second direction for which a call is registered to stop the elevator car at such farthest landing and to set the elevator car for travel in the first direction, said transfer means when operated permitting the stopping of the elevator car when traveling in the first direction at any of the intermediate landings approached by the elevator car for which a call is registered by the first control means.

43. An elevator system comprising a structure having terminal landings and a plurality of intermediate landings located between said terminal landings, an elevator car, mechanism mounting the elevator car for movement in first and second directions relative to the structure to serve the landings, and motive means for moving the elevator car relative to the structure, in combination with control means operable in cooperation with the motive means to move the elevator car relative to the structure and to stop the elevator car at predetermined landings, said control means comprising first control means at each of the intermediate landings and operable from the intermediate landings for registering calls for elevator service in a first direction from the respective intermediate landings, second control means at each of the intermediate landings and operable from the intermediate landings for registering calls for elevator service in a second direction from the respective intermediate landings, auxiliary control means for stopping the elevator car during travel in the first direction toward a first one of the terminal landings at each landing between the elevator car and such first one of the terminal landings for which the first control means are operated, said auxiliary control means stopping the elevator car during travel in the second direction towards the second one of the terminal landings at each landing between the elevator car and the second one of the terminal landings for which the second control means are operated, said auxiliary control means stopping the elevator car at each of the terminal landings reached by the elevator car and reversing the direction of travel for which the elevator car is set, timing means responsive to expiration of a substantial time of stopping of the elevator car at any of the intermediate landings while a call is registered by the control means for initiating a starting operation of the elevator car, transfer means operable for preventing the stopping of the elevator car during travel in the second direction at any of the intermediate landings approached by the elevator car in response to any calls registered by the second control means for an intermediate landing, said transfer means when operated permitting the stopping of the elevator car when traveling in the first direction at any of the intermediate landings approached by the elevator car for which a call is registered by the first control means, and signal means responsive to operation of the transfer means for indicating at least at each of the intermediate landings that the elevator system is conditioned for the operation permitted by the operated transfer means.

44. An elevator system comprising a structure having terminal landings and a plurality of intermediate landings located between said terminal landings, a plurality of elevator cars, mechanism mounting each of the elevator cars for movement in first and second directions relative to the structure to serve the landings, and motive means for moving the elevator car relative to the structure, in combination with control means operable in cooperation with the motive means to move each of the elevator cars relative to the structure and to stop the elevator car at predetermined landings, said control means comprising first control means at each of the intermediate landings and operable from the intermediate landings for registering calls for elevator service in a first direction from the respective intermediate landings,

second control means at each of the intermediate landings and operable from the intermediate landings for registering calls for elevator service in a second direction from the respective intermediate landings, auxiliary control means for stopping each of the elevator cars during travel in the first direction toward a first one of the terminal landings at each landing between the last-named elevator car and such first one of the terminal landings for which the first control means are operated, said auxiliary control means stopping each of the elevator cars during travel in the second direction towards the second one of the terminal landings at each landing between the last-named elevator car and the second one of the terminal landings for which the second control means are operated, said auxiliary control means stopping each of the elevator cars at each of the terminal landings reached by the last-named elevator car and reversing the direction of travel for which the elevator car is set, timing means responsive to expiration of a substantial time of stopping of each of the elevator cars at any of the intermediate landings while a call is registered by the control means for initiating a starting operation of the last-named elevator car, and transfer means operable for preventing the stopping of each of the elevator cars during travel in the second direction at any of the intermediate landings approached by the last-named elevator car in response to any calls registered by the second control means for an intermediate landing, said transfer means when operated permitting the stopping of each of the elevator cars when traveling in the first direction at any of the intermediate landings approached by the last-named elevator car for which a call is registered by the first control means.

45. An elevator system comprising a structure having terminal landings and a plurality of intermediate landings located between said terminal landings, a plurality of elevator cars, mechanism mounting each of the elevator cars for movement in first and second directions relative to the structure to serve the landings, and motive means for moving the elevator car relative to the structure, in combination with control means operable in cooperation with the motive means to move each of the elevator cars relative to the structure and to stop the elevator car at predetermined landings, said control means comprising first control means at each of the intermediate landings and operable from the intermediate landings for registering calls for elevator service in a first direction from the respective intermediate landings, second control means at each of the intermediate landings and operable from the intermediate landings for registering calls for elevator service in a second direction from the respective intermediate landings, auxiliary control means for stopping each of the elevator cars during travel in the first direction toward a first one of the terminal landings at each landing between the last-named elevator car and such first one of the terminal landings for which the first control means are operated, said auxiliary control means stopping each of the elevator cars during travel in the second direction towards the second one of the terminal landings at each landing between the last-named elevator car and the second one of the terminal landings for which the second control means are operated, said auxiliary control means stopping each of the elevator cars at each of the terminal landings reached by the last-named elevator car and reversing the direction of travel for which the elevator car is set, timing means responsive to expiration of a substantial time of stopping of each of the elevator cars at any of the intermediate landings while a call is registered by the control means for initiating a starting operation of the last-named elevator car, and transfer means operating in response to a predetermined service demand for preventing the stopping of each of the elevator cars during travel in the second direction at any of the intermediate landings approached by the last-

41

named elevator car in response to any calls registered by the second control means for an intermediate landing, said auxiliary control means being effective if each of the elevator cars while traveling in the second direction approaches a landing for which a call is registered by the first control means which is the farthest landing in the second direction for which a call is registered to stop the last-named elevator car at such farthest landing and to set the elevator car for travel in the first direction, said transfer means when operated

19

42

5 permitting the stopping of each of the elevator cars when traveling in the first direction at any of the intermediate landings approached by the last-named elevator car for which a call is registered by the first control means.
